TONE CHAMBER

Frank C. Carter, San Jose, Calif., assignor to
Florence Carter, Willits, Calif.

Application September 2, 1943, Serial No. 500,985

8 Claims. (Cl. 181—27)

This invention relates to a tone cabinet.

It primarily is aimed to provide a novel means or chamber for use in conjunction with or as an accessory to a loud speaker or the like of radio equipment, to improve reception and attain perfect clarity of tone, either instrumental or vocal, in volume and without distortion.

It is further aimed to provide a construction attaining the results mentioned by use of hollow walls and sound boxes, preferably in combination, the sound boxes being arranged above and below the loud speaker, and the higher one being closer to it.

The more specific objects and advantages will become apparent from a consideration of the description following taken in connection with accompanying drawings illustrating an operative embodiment.

In said drawings:

Figure 1 is a top or plan view of the tone cabinet;

Figure 2 is a front elevation thereof;

Figure 3 is a central vertical sectional view taken longitudinally through the tone cabinet on line 3—3 of Figure 2.

Figure 4 is a transverse vertical sectional view taken on the line 4—4 of Figure 3; and

Figure 5 is a fragmentary horizontal sectional view taken below the upper sound box on the plane of line 5—5 of Figure 2.

Referring specifically to the drawings wherein like reference characters designate like or similar parts, my improved tone cabinet has a vertically disposed rear wall at 10, to which is fastened a conventional loud speaker of radio apparatus or the equivalent as at 11 in position, so that the sound will be discharged within the tone chamber.

Parallel but in spaced relation to each other are two side walls at 12, attached to and extending forwardly from the rear wall 10. These side walls are in practice approximately one inch thick, made up of plywood panels as at 13 spaced apart to render the walls hollow, and secured to wooden battens as at 14, to rigidify the structure. The rear wall 10 also may be secured to the battens 14 adjacent thereto, and such rear wall also is adapted to be made of plywood like the walls or panels 13. It is to be noted that each inner panel 13 has an arcuate groove or slot 15 cut into the same to facilitate vibration of the panels by the sound waves.

At the top and bottom of the improved tone chamber I provide sound boxes as at 16 and 17. The sound box 16 is at the rear of the tone chamber, while the sound box 17 is at the front there-

of. The lower wall of sound box 16, designated 18, is inclined forwardly and upwardly, and the upper wall 19 of the lower sound box 17 is disposed at the same angle. In the case of the sound box 16 rear wall 10 constitutes the rear wall of the sound box. All walls of the sound boxes 16 and 17 are preferably made from plywood or equivalent material. The sound openings 20 and 21 are provided in the walls 18 and 19 of the sound box.

It is to be understood that the tone cabinet may be built in any desired sizes and that the size will depend upon the size of the loud speaker with which it cooperates.

I find in use that with the sound introduced into the tone chamber from the loud speaker 11 or the equivalent, there is perfect clarity of tone, either instrumental or vocal; there is volume without distortion, a lack of harshness, greater carrying power; and that many notes that are lost by the ordinary radio loud speaker, especially when listening to orchestra music, are quite distinct when using my improved tone cabinet, the result being due in part to the hollow side wall and to the sound boxes, in part, and the general arrangement of the latter.

Various changes may be resorted to provided that they fall within the spirit and scope of the invention.

30 I claim as my invention:

1. A structure of the class described having a wall through which sound is adapted to be introduced, and side walls in spaced relation extending therefrom, said side walls being hollow and slotted so as to have restricted communication with the space between them.

2. A structure of the class described having a wall through which sound is adapted to be introduced, and side walls in spaced relation extending therefrom, said side walls being hollow, comprising spaced-apart panels, the innermost panels having slots therein so as to have restricted communication with the space between them.

3. A structure of the class described having a wall through which sound is adapted to be introduced, and side walls in spaced relation extending therefrom, said side walls being hollow, and upper and lower sound boxes disposed between said sidewalls.

4. A structure of the class described having a wall through which sound is adapted to be introduced, and side walls in spaced relation extending therefrom, said side walls being hollow, and upper and lower sound boxes, the upper sound box

extending rearwardly further than the lower sound box.

5. A structure of the class described having a wall through which sound is adapted to be introduced, and side walls in spaced relation extending therefrom, said side walls being hollow, and upper and lower sound boxes, the upper sound box extending rearwardly further than the lower sound box, said sound boxes having facing inclined walls provided with sound openings.

6. A structure of the class described having a wall through which sound is adapted to be introduced, and side walls in spaced relation extending therefrom, said side walls being hollow, and upper and lower sound boxes, the upper sound box 15 extending rearwardly further than the lower sound box, said sound boxes having facing in-

clined walls provided with sound openings, and arcuate slots in the inner panels of said walls.

7. A structure of the class described having a wall through which sound is adapted to be introduced, side wall, and upper and lower sound boxes in front of the first-mentioned wall and between the sidewalls, one of said sound boxes being spaced from the first mentioned wall.

8. A structure of the class described having a wall through which sound is adapted to be introduced, side walls, and upper and lower sound boxes in front of the first-mentioned wall and between the side walls, one of said sound boxes being spaced from the first mentioned wall, said sound boxes having facing walls disposed at an upward angle, the latter walls having openings therein.
